UNITED STATES PATENT OFFICE.

JAMES H. NORTHROP, OF HOPEDALE, MASSACHUSETTS, ASSIGNOR TO THE
NORTHROP LOOM COMPANY, OF SACO, MAINE.

CLOTH-EVENING DEVICE.

SPECIFICATION forming part of Letters Patent No. 569,586, dated October 13, 1896.

Application filed July 1, 1896. Serial No. 597,665. (No model.)

To all whom it may concern:

Be it known that I, JAMES H. NORTHROP, of Hopedale, county of Worcester, State of Massachusetts, have invented an Improvement in Looms, of which the following description, in connection with the accompanying drawings, is a specification, like letters on the drawings representing like parts.

In looms provided with automatic filling-supplying mechanism, as in the well-known "Northrop" loom, one form of which is shown in United States Patent No. 529,940, it often happens, when the filling is changed, that by reason of the time when the weft-fork detects the absence of the filling there will be one to three picks of filling left absent from the cloth. This would naturally make a thin place, and the take-up mechanism is usually arranged to let back one or more teeth to provide for the absence of filling. If, however, the take-up is set for one pick of filling, and the cloth may lose one, two, or three picks, as stated, the take-up will not operate when the two or three picks are absent.

This invention has for its object the production of a simple cloth-evening device adapted to operate when the filling is changed to first stretch the cloth in front of the reed, said device thereafter being relaxed to thus loosen the cloth, so that the absence of picks of filling will not be so marked.

The operation of the take-up is also assisted by the device to be described, as when the usual pawl is lifted there may not be enough inherent strain in the cloth to reverse, by an amount permitted by the escapement-pawl, the roll on which the cloth is wound.

As is well known, it is customary, when weavers change the filling on ordinary looms, to press the shuttle or their hand along the face of the goods to bring a strain on the cloth between the take-up and the reed, and this invention accomplishes mechanically and automatically what the weaver thus does by hand.

Figure 1 is a transverse sectional view of a sufficient portion of a loom to be understood, with my invention embodied therein; and Fig. 2 is a detail, in elevation and partly

in section, of the mechanism controlled by 50 failure of the weft and which operates the cloth-evening device.

The loom-frame A, breast-beam A¹⁰, the lay A³, the rod or rock-shaft d', the knock-off lever b⁵, resting normally against or close to 55 the shipper-lever, its free end being carried forward to be acted upon by the weft-fork mechanism, the stand b⁷, mounted on the breast-beam and having a suitable guideway for the reciprocating slide b⁹, upon which is 60 pivoted at b¹⁰ the weft-fork b¹², the check c⁴ to aid in turning the weft-fork about its pivot b¹⁰ after it has been tilted, and the projection c⁶ on the rear end of the weft-fork slide and against which normally acts a lever c⁷, pivoted at c⁸ and joined by a link c⁹ to an arm c¹⁰ of the rock-shaft d', are and may be all substantially as shown in United States Patent No. 529,943, wherein like letters are employed to designate like parts. 70

In Fig. 2 herein the normal condition of the rock-shaft d' and lever c⁷ is shown when the loom is weaving regularly.

Below and at the front of the breast-beam A¹⁰ (see Fig. 1) I pivotally mount at f a swinging normally depending board F, extending across the loom and as long as or longer than the width of the cloth C, which latter passes over the outer lower corner f^X of the board F on its way to the roll G and cloth-roll C'. 75 A dog f' is pivoted at f² on the rear or inner side of the board or evener F and has near its free end an upturned lug or projection f³, normally out of the path of movement of a bunter B on the lay, as shown in full lines. 80

The rock-shaft d' has adjustably secured thereto by a set-screw 5 an arm d², having an offset end d³, extended beneath the dog f' and controlling the position of the latter, the curved form of the dog facilitating its easy 90 movement by the controlling-arm d². Now when the rock-shaft d' is turned to elevate the arm d² into dotted-line position, Fig. 1, as it will be at each pick wherein the filling is absent, by means of the devices shown in 95 Fig. 2, it will be obvious that the dog f' will be moved into position to enable the bunter B on the forward stroke of the lay to engage

the projection f^3 and move the dog forward, thereby swinging the evener F into dotted-line position, Fig. 1.

The edge f^x of the evener acts upon the web of cloth in an outward and upward direction, exerting a strain thereupon between the take-up and the reed and loosening up the cloth in front of the latter when the evener returns to normal position. As has been stated, this strain upon the cloth assists the operation of the take-up in reversing the cloth-roll, and it will be obvious that the evening device will be operated each pick that the weft-fork detects the absence of filling, so that there will be a stretching of the cloth for each pick void of filling, and consequently the thin place in the cloth will be entirely obviated or so counteracted as to be hardly noticeable. When the loom is again running properly, the rock-shaft d' resumes its normal position and the dog for the evening device resumes its inoperative position.

So far as I am aware, it is broadly new to provide means to automatically stretch the cloth between the reed and the take-up upon the absence of the weft for one or more picks, the operation of such means being controlled by such failure or absence of the weft or filling, and accordingly my invention is not restricted to the precise construction and arrangement herein shown.

Having fully described my invention, what I claim, and desire to secure by Letters Patent, is—

35 1. In a loom, a normally inoperative device to act upon and stretch the cloth between the reed and take-up, means to operate said device, and controlling mechanism for said means, operative upon failure of the weft, to thereby operate the cloth-stretching device, substantially as described.

45 2. In a loom a weft-fork, a normally inoperative device to act upon and stretch the cloth between the reed and take-up, a dog carried by said device, a coöperating bunter, and means controlled by the weft-fork to move said dog into position to be engaged by the bunter upon failure of the weft, substantially as described.

3. In a loom a weft-fork, the lay, a bunter thereon, a pivotally-mounted device adapted to act upon and stretch the cloth between the reed and take-up, a normally inoperative dog on said device, and means controlled by the weft-fork to move said dog into position to be acted upon by the bunter when the weft fails, whereby the cloth will be stretched and slackened in front of the reed, substantially as described.

4. In a loom, a pivotally-mounted bar to act upon and stretch the cloth between the reed and take-up, a dog on said bar, a coöperating bunter, and a dog-controlling device operative upon failure of the weft to move said dog into position to be struck by the bunter, whereby the pivoted bar will act upon and stretch the cloth, substantially as described.

5. In a loom a weft-fork, the breast-beam, a swinging board pivotally mounted below it and to act upon the under side of the cloth to stretch it, and means controlled by the weft-fork, to swing said board outwardly and upwardly against the cloth when the weft fails, substantially as described.

6. In a loom, a weft-fork, a normally inoperative device to act upon the cloth and stretch it between the reed and take-up, a dog and a coöperating bunter, to operate said device, a rock-shaft under control of the weft-fork, and means secured to said rock-shaft to move the dog into position to be struck by the bunter, substantially as described.

7. In a loom, a normally inoperative device to act upon and stretch the cloth between the reed and take-up, and means operative upon failure of the weft to move the said device to act upon and stretch the cloth in front of the reed, substantially as described.

In testimony whereof I have signed my name to this specification in the presence of two subscribing witnesses.

JAMES H. NORTHROP.
